CLAIM

The ornamental design for a loudspeaker, as shown and described.

DESCRIPTION

FIG. 1 is a perspective view of a loudspeaker in accordance with our invention;

FIG. 2 is a bottom plan view of the loudspeaker shown in FIG. 1;

FIG. 3 is a top plan view of the loudspeaker shown in FIG. 1;

FIG. 4 is a front view of the loudspeaker shown in FIG. 1;

FIG. 5 is a right side view of the loudspeaker shown in FIG. 1;

FIG. 6 is a rear view of the loudspeaker and shown in FIG. 1; and,

FIG. 7 is a left side view of the loudspeaker and shown in FIG. 1.

The broken line showing a stand connector on FIG. 2 is for illustrative purposes only and forms no part of the claimed design.
